UNITED STATES PATENT OFFICE.

KAZMER WOJTAŚIEWICZ, OF CLEVELAND, OHIO.

COMB-CLEANING DEVICE.

Application filed September 15, 1927. Serial No. 219,629.

The present invention relates to comb cleaning devices and has for its main object the provision of a device for cleaning combs by means of a rotatable brush.

Another object of the invention is the provision of a comb cleaner wherein a comb to be cleaned is held in position while a rotatable brush is revolved for the purpose of cleaning the comb.

Another object of the present invention is to generally improve the construction of a comb cleaner.

With the above general objects in view and others that will appear as the nature of the invention is better understood the same consists in the novel construction, combination and arrangement of parts herein-after more fully described, illustrated on the accompanying drawings and pointed out in the appended claims.

In the drawings forming a part of this application and in which like designating characters refer to corresponding parts throughout the several views,

Fig. 1 is a side view, partly in elevation and partly in section, of the device;

Fig. 2 is a top view of the device with the cover removed;

Fig. 3 is a transverse cross-sectional view on line 3—3 of Fig. 2; and

Fig. 4 is the end view of the device.

Referring to the drawings in detail, the invention embodies two end walls 10 and 11 terminating in supporting legs 12 and 13. Each of said legs is provided with a plate 14 with aperture 15 therein by means of which the device may be affixed or mounted upon a table or any other suitable support.

The two end walls 10 and 11 are joined or connected by means of shelf 16, front wall 17 and rear wall 18. Said shelf and said walls are affixed to each of said end walls 10 and 11 by means of screws or nails 19.

The invention further embodies a metallic strip 20 which is mounted at its ends in end walls 10 and 11 and is substantially above the front wall 17. Forwardly of said metallic strip 20 is another strip 21 likewise mounted at its ends in the end walls 10 and 11. Embedded by its lower edge in the upper end of front wall 17 and by its upper end in said strip 21 is a protecting wall 22, made of glass or of any other suitable material and is likewise affixed by its ends in the

end walls 10 and 11. The purpose of said protecting wall 22 is to deflect any impurities that may fall from the comb into the space made by the front wall 17 and rear wall 18 and into drawer 23, said drawer being positioned upon shelf 24 and directly below rotatable brush 25.

An L-shaped wooden strip 26 is spaced from said metallic strip 20 and is likewise embedded by its ends in the end walls 10 and 11. A narrower metallic strip 27 is receivable within said wooden strip 26 and is for the purpose of strengthening the structure of the device. The inner faces of said strips 26 and 27 are covered by layer 70 of felt 28 which forms a protective covering for the comb when the same is received within the device for the purpose of cleaning the same.

In front of the inner face of metallic strip 20 there is positioned a resilient metallic plate 29 having upon its inner face a layer of felt 30.

Screw 31 is passed through the central portion of the metallic strip 20 and is adapted to contact with the resilient plate 29 by its inner end, as seen on Fig. 2. Between strips 20 and 26, or more specifically between felt layers 28 and 30 there is a longitudinal slit 32 into which the comb 33 is positioned and is adapted to embed itself by its teeth into the rotatable brush 25 as seen on Fig. 3. On a plane with the lower end of the metallic strip 20 there is a pair of wires 34 which traverse said slit 32 and which are adapted to pass in between the teeth of the comb for the purpose of supporting the body of the comb thereupon. The outer ends of said wires 34 are provided with loops 35 for the purpose of passing screws 36 therethrough by means of which said wires are mounted upon the lower end of strip 20.

On inserting comb 33 into slit 32 screw 31 is turned until resilient plate 29 with its felt layer 30 are brought by their central portions to the comb which will be firmly held in position by the pressure exerted thereupon by said plate 29 and felt 30 on its one side and by strips 26 and 27 and felt layer 28 on its other side, as is apparent from Fig. 2.

Celluloid cover 37 mounted upon the upper ends of end walls 10 and 11 provides a housing or covering for the mechanism hereinabove described and adds to the neat

appearance of the device. Said cover is provided with slit 38 registering with slit 32, permitting ready insertion of the comb into the device.

5 3. Plates 38 passing over said celluloid cover 37 at the ends thereof hold said cover in position upon the end walls 10 and 11. Screws 39 passing through said plates 38 and cover 37 affix said plates and said cover 10 to said end walls 10 and 11.

Said rotatable brush 25 has shaft 40 which is mounted within end walls 10 and 11 and is adapted for rotation therewithin. One of the ends of said shaft 40 projects beyond 15 wall 11 and has a pinion 41 mounted thereupon. Said pinion meshes with a central gear 42 which is mounted upon the shaft 43 which is affixed to said end wall 11. Said central shaft 42 meshes with gear 43 20 mounted upon shaft 44 which is mounted in end wall 11 and is adapted for rotation. The end of shaft 44 is square and receives a crank lever 45 which has at its outer end crank handle 46. By turning crank lever 25 45 by handle 46 gear 43 rotates and through gear 42 the rotation will be imparted to pinion 41 and in consequence thereof brush 25 will likewise be rotated with its shaft 40 which bristles of said brush striking upon 30 the comb 33 and in between the teeth will drive all the dirt from the teeth which dirt will deflect from the protective wall 22 and will fall into drawer 23 from where it can be removed upon withdrawing said drawer 35 23 from beneath brush 25.

While there is described herein a preferred embodiment of the present invention, it is nevertheless to be understood that minor changes may be made therein without departing from the spirit and scope of the invention as claimed.

What I claim as new is:

1. A comb cleaner comprising a pair of end walls, a pair of strips mounted upon said end walls and spaced from each other for 45 inserting a comb therewithin, a resilient plate adjacent one of said strips, a screw passing through said latter strip and bearing against said plate for engaging said comb when the same rests between said strips, means associated with one of said strips for providing upright support for the comb, a rotatable brush mounted between said end walls, said brush being adapted to engage the teeth of the comb, and means for 50 rotating said brush.

2. A comb cleaner comprising a pair of end walls, a pair of strips mounted in said end walls and spaced from each other for effecting a slit for receiving a comb therewithin, a resilient plate adjacent one of said strips, means associated with said latter strip and bearing against said plate for engaging the comb when the same rests within 60 said slit, and a rotatable brush mounted between said end walls.

3. A comb cleaner comprising a pair of end walls, a pair of strips mounted in said end walls and spaced from each other for effecting a slit, a resilient plate adjacent one 70 of said strips, adjustable means associated with said latter strip and bearing against said plate for holding the comb in position within said slit, a plurality of wire strands associated with one of said strips for providing upright support for the comb, a rotatable brush mounted between said end walls, said brush being adapted to engage the teeth of the comb, and means for rotating said brush.

In testimony whereof I affix my signature.
KAZMER WOJTASIEWICZ.
